UNITED STATES PATENT OFFICE

2,659,327

FURNACE ROOF

Fritz Höning, Vienna, Austria, assignor to Veitscher Magnesitwerke-Aktiengesellschaft, Vienna, Austria, a firm

Application July 23, 1947, Serial No. 763,017

Section 1, Public Law 690, August 3, 1946
Patent expires August 23, 1960

6 Claims. (Cl. 110—99)

1

The invention relates to furnace roofs and more particularly to roofs of furnaces of the open-hearth type built up of bricks of relatively high specific weight—such as bricks made of chrome magnesite—which are not apt to be cemented together fast but have properties which are excellent regarding refractoriness and small wear and tear and which result therefore in increase of durability of the roof.

Some types of roof built up of bricks of such kind are known. It is the principal object of my invention to attain a greater strength of the furnace roof than is attainable with constructions of known types by providing a close and fast connection between said bricks and iron girders bent in conformity with the arch of the roof and capable of being deformed during the rise of the roof under the influence of heat, whereby the roof may be built up wholly or partly of such armored rows of bricks forming the ribs or stringers of the roof. This temporary deformation or yielding of the girders is attained by an appropriate dimensioning of them so that, on the one hand, they form a rigid back for side by side lying bricks of a row thus holding them in their proper position in the arch but are, on the other hand, not stiff enough to resist the thrust of the rising row of bricks as a whole.

Another object of my invention resides in the particular construction of a furnace roof which is to be built of bricks of relatively high specific weight, by interposing intermediate rows of bricks between said supporting ribs and by connecting in a peculiar way the arched girders with the bricks supporting them.

A further object of my invention relates to the mode of suspension of the roof by suspending the arched iron girders on rigid beams whereby the weight of the roof is carried partly by said beams. There are known, of course, various types of suspended roofs of which the ribs—each consisting of a row of supporting bricks—are suspended in different ways by means of various construction elements. In comparison with these types a roof built up according to the invention is extremely simple and inexpensive, and is distinguished by offering a possibility of keeping the yielding of the roof during its rise under control. According to the invention a roof of such kind may be built up wholly or partly of ribs each of which consists of an arched row of bricks and of an arched iron girder connected with the row of bricks and is capable of temporary deformation during the rise of the roof.

Other features of this invention will appear

2

as the following description thereof proceeds.

The drawing illustrates two embodiments of roof constructions according to the invention.

Fig. 1 is a transverse sectional view of a suspended roof;

Figs. 2 and 3 illustrate by way of example two embodiments of roof suspensions in a cross-section on a plane taken at right angles to the plane of Fig. 1;

Fig. 4 is a detail perspective view (partly in section) showing a means of suspension of individual bricks;

Fig. 5 is a fragmentary view similar to that of Fig. 1 but showing a modified form of an abutment for a rib.

Referring more particularly to the embodiment of my invention as shown in Figs. 1 and 2, the roof is built up of suspended bricks 1 forming the supporting ribs and of intermediate rows or

areas of bricks 2. The suspended bricks 1 are provided with lateral projections 8 destined for the connection with the arched girders 10. The abutment of the roof may be made movable on springs by any means. The drawing shows schematically a spring device 14 for the abutment 12 of a rib supporting an arched girder 10 (for instance a T-girder). The girders 10 may be sus-

pended adjustably on rigid beams 3 of the iron structure 6 of the furnace. Figs. 2 and 3 show two embodiments of this suspension which may be performed by means of screwed tie-rods 7, as

shown in Fig. 2, or by means of wire loops 7a, as shown in Fig. 3, whereby a few suspension members of this sort may be sufficient. Advantage-

ously the suspended bricks may be connected with the girder supported by them by wire loops 9 which may be formed with particular advan-

tage as to simplicity and low costs out of a single continuous length of wire for all bricks of a rib (Fig. 4). Alternatively, of course, these bricks

may be gathered up in pairs or in groups (as shown in Figs. 2 and 3) by means of separate loops. As shown in the drawing the connection of the bricks with the close adjacent girder is made in such a way that with regards to the rise

of the roof these bricks and their arched girder form a shaped unit.

In arrangements of known types in which the bricks of the roof are spaced apart from the arched iron girders, it is necessary to brace the roof against the girders with the aid of specially constructed, non-buckling spacing members. In contradistinction thereto an arrangement according to this invention, comprising the use of loops 50 formed of a continuous length of wire at least for

a group of bricks for connecting the bricks with the arched girder 10 lying close to them, is much more simple and inexpensive. In building up such a roof the arched iron girders are laid on after completion of the brick roof on the arch centering and subsequently connected with the bricks by the tightening of the wire loop.

In place of the arched iron girders 10 pressure straps 4 may be used (see Fig. 5) which are connected to the iron structure of the furnace by any known spring device. In the embodiment as shown the strap 4 is put under tension by a spring 5 and thereby pressed on the roof whereby by virtue of the fast connection of the bricks with their adjacent strap the proper position of neighboring bricks in the roof remains unaltered. Owing to the springy abutment, however, the pressure straps do not prevent the yielding of the roof as a whole.

As the loops lie close to the arched girders 10 or to the pressure straps 4, respectively, without projections, hole-guides or the like, a longitudinal displacement of the girders or of the bricks can take place in conformity with the different expansion of both caused by heat.

Having now fully disclosed my invention, what I claim as new and desire to secure by a patent of the United States of America is:

1. A furnace roof comprising an iron frame, a brick vault including a plurality of rows of bricks, each of said rows forming an arched rib, a plurality of arched reinforcing members respectively overlying said ribs and making contact with the bricks thereof over substantially the full length of each rib, supporting means individually securing each brick of a rib to the adjacent reinforcing member in such manner as substantially to prevent relative radial movement between said bricks and said member while permitting some relative longitudinal adjustment thereof, each of said reinforcing members being sufficiently deformable to enable said vault to expand and rise under the influence of heat, abutment means bearing endwise on each of said ribs, guide means on said frame enabling horizontal movement of said abutment means toward said ribs, spring means urging said abutment means into contact with said ribs, and suspension means supporting said reinforcing members from said frame.

2. A furnace roof according to claim 1, further comprising a plurality of intermediate brick sections alternating with and supported by said rows of bricks.

3. A furnace roof according to claim 1 wherein each of said reinforcing members comprises an arched girder having a bottom flange, said flange bearing upon the bricks of the corresponding rib and being maintained in direct contact therewith by said supporting means.

4. A furnace roof comprising an iron frame, a brick vault including a plurality of rows of bricks, each of said rows forming an arched rib, a plurality of arched reinforcing members respectively overlying said ribs, supporting means individually securing each brick of a rib to the adjacent reinforcing member in such manner as substantially to prevent relative radial movement between said bricks and said member, each of said reinforcing members being sufficiently deformable to enable said vault to expand and to rise under the influence of heat, abutment means bearing endwise on each of said ribs, guide means on said frame enabling horizontal movement of said abutment means toward said ribs, spring

means urging said abutment means into contact with said ribs, and suspension means supporting said reinforcing members from said frame, each of said reinforcing members comprising a curved pressure strap and having an extremity engaged by said spring means, thereby exerting a downward pressure upon the associated rib.

5. A furnace roof comprising a brick vault including a plurality of rows of bricks, each of said rows forming an arched rib, a frame supporting said vault, a plurality of arched reinforcing members respectively overlying said ribs, and supporting means individually securing each brick of a rib to the adjacent reinforcing member in such manner as substantially to prevent relative radial movement between said bricks and said member, each of said reinforcing members being sufficiently deformable to enable said vault to expand and to rise under the influence of heat, said bricks being provided with projections, said supporting means including supple wire means looped around a reinforcing member and undersliding the projections of the bricks of the associated rib while lying snugly against said bricks over a substantial portion of each projection, said wire means maintaining said bricks and said member in close contact with one another.

6. A furnace roof comprising a brick vault including a plurality of rows of bricks, each of said rows forming an arched rib, a frame supporting said vault, a plurality of arched reinforcing members respectively overlying said ribs, abutment means bearing endwise on each of said ribs, guide means on said frame enabling horizontal movement of said abutment means toward said ribs, spring means urging said abutment means into contact with said ribs, and supporting means individually securing each brick of a rib to the adjacent reinforcing member in such manner as substantially to prevent relative radial movement between said bricks and said member, each of said reinforcing members being sufficiently deformable to enable said vault to expand and to rise under the influence of heat, said bricks being provided with projections, said supporting means including wire means looped around a respective reinforcing member and engaging said projections in such manner as to suspend said bricks from the reinforcing member while maintaining said bricks and said member in close contact with each other, said wire means including a continuous length of wire engaging a plurality of bricks having the said projections thereof facing in the same direction.
